LOOSE LEAF BINDER

Paul O. Unger, Elmhurst, Ill., assignor to Wilson-Jones Company, Chicago, Ill., a corporation of Massachusetts

Application February 12, 1936, Serial No. 63,481

13 Claims. (Cl. 129—24)

This invention relates to a loose leaf binder of the record book type, and more particularly to means for controlling the movement of the pintle slides.

It is an object of this invention to provide simple and efficient means that move automatically, when the pintle slides have been manually moved into open position, into the path of travel of the pintle slides to retain them in open position. It is a further object of this invention to provide a trigger with means engaged by the cover, when the cover is moved to closed position, to move the trigger out of pintle engaging position. Other objects of this invention will become apparent upon reading the following description, taken in conjunction with the accompanying drawings, in which

Figure 1 is a fragmentary perspective view of a loose leaf binder embodying the invention;

Figure 2 is a transverse sectional view through the binder, showing the cover about to trip the pintle locking mechanism;

Figure 3 is a transverse sectional view through the binder showing one sheet retaining post engaging the pintle slides;

Figure 4 is a top plan view of the back of the binder with parts broken away to facilitate the illustration;

Figure 5 is a longitudinal sectional view through the back of the binder taken along the line V—V of Figure 4;

Figure 6 is a fragmentary perspective view showing the pintle slide in open position;

Figure 7 is a view similar to Figure 6 showing the pintle slide in closed position;

Figure 8 is a fragmentary detail of the post aligning strip;

Figure 9 is a detail view of the trigger; and

Figure 10 is a fragmentary detail of the pintle slide.

In the drawings, the reference numeral 2 indicates a back member to opposite sides of which cover members 3 are hinged, as indicated at 4. The cover members 3 are preferably formed of light wood, such as basswood, but may be formed of binder's board or any similar material. The cover members 3 are provided with a covering 5 of leather or similar material to enhance the appearance of the finished book. The cover members 3 are secured to the hinges 4 by means of hinge plates 6 which are provided with a plurality of prong members 7 adapted to project into the cover members 3. The cover members 3 are recessed, as indicated at 8, to allow clearance space for the sheet retaining structure so the cov-

ers may lie flat against the sheets 9 without leaving any gap. The inner surface of each cover member 3 is provided with a lining 10 of paper, fabric or any other suitable material.

The back member 2 includes a rounded back section 11 and a substantially flat plate member 12 having its opposite longitudinal edges secured to the hinges 4. The plate member 12 adds rigidity to the back member 2, and serves as a support for the sheets 9. The rounded back section 11 is provided with a covering of leather or other suitable material, as indicated at 13, to harmonize with the covering material 5.

A tubular sheath 14 is secured to the flat back plate 12 adjacent each hinge by means of a flange 15. The back plate 12 is depressed along its longitudinal edges, as indicated at 16, so that the exposed surface of the flange 15 is flush with the corresponding surface of the back plate 12. Each tubular sheath 14 is notched, as indicated at 17, in a plurality of predetermined positions. The notches 17 are each adapted to receive one end of any sheet retaining post 18 upon which the sheets 9 may be impaled. A pintle slide 19 is slidably mounted in each tubular sheath. One end of the sheath is closed, as indicated at 20, to prevent access to the pintle slide from that end.

A tension spring 21, having one end secured to a pin 22 fixed adjacent the closed end 20 of the tubular sheath 14 and its other end secured to the inner end 23 of the pintle slide, exerts a constant force urging the pintle slide inwardly towards closed position. Each pintle slide 19 is provided with a plurality of pintles 24 adapted to bridge the notches 17 when the pintle slide 19 is in its innermost or closed position. The inward movement of the pintle slide 19 is limited by means of the handle 25 which facilitates opening or outward movement of the pintle slide against the action of the spring 21. The handle 25 is provided with a flat surface 26 which projects over the top surface of the sheets 9, as shown most clearly in Figure 1, so that the handle 25 may be readily engaged by the operator's finger when it is desired to move either pintle slide to open position. The flat surface also prevents the handle 25 from digging into the flesh of an operator's finger. Each handle 25 is removably secured to its pintle slide by means of a screw 27.

Each sheet retaining post 18 is apertured at both ends, as indicated at 28, so that when either end of any post 18 is properly positioned in any notch 17, one pintle 24 will pass through its aperture 28 to secure the post to the binder when the proper pintle slide is moved inwardly. When the

5 pinte slide 19 is pulled outwardly against the action of the spring 21 a distance sufficient to disengage the pintles 24 from the apertures 28, the pinte slide is automatically held against accidental return to closed position upon release of the handle 25.

10 The mechanism for holding the pinte slide 19 in open position includes a trigger 29 pivoted to the back plate 12, by means of a rivet 30, to move substantially transversely of the binder into and out of the plane of the pinte slide. The trigger 29 is provided at its free end with a flange 31 which is bent at right angles to the body portion of the trigger and extends substantially parallel to the pinte slide. The flange 31 has a locking tooth 32 extending therefrom. The tubular sheath 14 is cut away, as indicated at 33 (Figure 5), to enable the locking tooth 32 to lie against the pinte slide 19. The pinte slide 19 is provided with a recess or notch 34 in its lower edge. The recess 34 is dimensioned to snugly receive the locking tooth 32 and is positioned so that the pinte slide is in its open position, indicated in Figure 6, when the locking tooth is positioned in the recess.

15 A spring 35, secured to the back plate 12 by means of a bracket 36, exerts a constant force against the flange 31 to urge the locking tooth 32 into the path of travel of the pinte slide. The bracket 36 is secured to the back plate 12, by means of rivets 30 and 37. The flange 31 is provided with a projection 38 bent at right angles thereto. The wall 14' of the tubular sheath 14 is provided with an aperture 38' through which the projection 38 extends. The projection 38 extends beyond the sheet retaining mechanism far enough to be engaged by the hinge plate 6 during movement of the cover to closed position when the cover is about fifteen degrees removed from its closed position. The cover moves the projection 38 inwardly and the locking tooth 32 moves out of the path of travel of the pinte slide 19. As soon as the tooth 32 is disengaged from the notch 34 the tension spring 21 automatically propels the pinte slide to closed position.

20 The projection 38 is made long enough to strike the hinge plate 6 before the cover is completely closed as indicated in Figure 2, because sometimes a canvas jacket is placed on the covers and if the projection were designed to engage the hinge plate later in the closing movement of the cover the jacket might interfere with the tripping action. As the binder is designed, even 25 a pencil or a small stack of papers resting on the top surface of the sheets will not interfere with the pinte locking mechanism.

25 The spring 35 is preferably formed from a single piece of spring wire 39 which is twisted 60 so that its other end 40 exerts force against the lower edge of the pinte slide 19 in a plane extending at right angles to the plane in which the force of the spring 35 is exerted. The pinte slide 19 is provided with a notch 41 in its lower edge. As 65 shown in Figure 7, the notch 41 is positioned near the bent end 42 of the spring 40 when the pinte slide 19 is in its normal closed position. In this position the handle 25 abuts the end of the sheath 14 to prevent further inward movement 70 of the pinte slide. When the binder is completely filled, the handle 25 is removed, and the spring 21 propels the slide inwardly beyond its normal closed position. The end 42 snaps into engagement with the notch 41 and permanently locks the pinte slide in closed position.

5 Although it is not essential, the binder is preferably provided with post aligning means to insure registration of the apertures 28 with the pintles 24 before the covers are closed. The preferred form of post aligning means is fully disclosed in my prior application Serial No. 37,852, filed August 26, 1935, which issued as Patent No. 2,092,194, on September 7, 1937, and will not be described in detail. The post aligning means includes a resilient strip 43 having a longitudinal groove 44 adapted to engage the ends of the sheet retaining posts 18. A plurality of flat springs 45 cooperate with the strip 43 to impart a relatively stiff spring action to the strip to hold it in contact with the ends of the sheet retaining posts. 10 The resilient strip 43 is secured to the binder by means of a plurality of hinge sleeves 46 which fit in and form part of the hinge 4. The strip 43 is provided with a notch 38' through which the projection 38 extends.

15 Although I have described the preferred embodiment of my invention in considerable detail, it will be understood that the description thereof is intended to be illustrative, rather than restrictive, inasmuch as many structural details may be 20 modified or changed without departing from the spirit or scope of my invention. Accordingly, I do not desire to be restricted to the exact structure described, except as limited by the appended claims.

25 I claim:

1. In a loose leaf binder, a back member, a cover hinged to said back member, a tubular sheath secured along one edge of said member, a pinte slide in said sheath, said pinte slide being provided with a recess, a trigger movable substantially transversely of said back member in a plane parallel to the plane of said back member, means to move said trigger into said recess automatically when said recess is in registration with said trigger, and means for automatically moving said trigger out of said recess when said cover is closed.

35 2. In a loose leaf binder, a back plate, a tubular sheath secured along one edge of said back plate, a pinte slide in said sheath, said pinte slide being provided with a recess, a trigger pivoted to said back plate and movable in a plane parallel to the plane of said back plate, and a spring urging said trigger towards said pinte slide to cause said trigger to engage said pinte slide when said pinte slide is moved to bring said recess into registration with said trigger.

40 3. In a loose leaf binder, a back member, a tubular sheath secured along one edge of said back member, a pinte slide in said sheath, the plane of said pinte slide being substantially perpendicular to the plane of said back member, said pinte slide being provided with a recess, a spring urging said pinte slide inwardly, means for manually pulling said pinte slide outwardly against the action of said spring, a trigger positioned out of the plane of said pinte slide, and means automatically moving said trigger into the plane of said pinte slide and into said recess when said pinte slide has been moved outwardly a distance sufficient to bring said recess into registration with said trigger.

45 4. In a loose leaf binder, a back plate, a tubular sheath secured along one edge of said back plate, a pinte slide in said sheath, said pinte slide being provided with a recess, a spring urging said pinte slide inwardly, means for manually pulling said pinte slide outwardly

against the action of said spring, a trigger positioned out of the plane of said pintle slide, and means to move said trigger substantially transversely in a plane parallel to said back plate 5 into the plane of said pintle slide and into said recess to hold said pintle slide in predetermined position when said pintle slide is pulled outwardly against the action of said spring.

5. In a loose leaf binder, a cover, a pintle slide movable longitudinally of said binder, a trigger positioned adjacent one side of said pintle slide, said trigger being movable into engagement with said pintle slide to prevent longitudinal movement of said slide, and a projection 10 extending from said trigger to the opposite side of said pintle slide, said cover when moved to closed position being adapted to engage said projection to move said trigger out of the plane of said pintle slide.

20. 6. In a loose leaf binder, a back member, a cover hinged along one edge of said back member, a tubular sheath secured adjacent said back member, a pintle slide in said sheath, the plane of said pintle slide being substantially perpendicular to the plane of said back member, a trigger pivoted to swing into the path of travel of said pintle slide, and a projection on said trigger adapted to project beyond the outer edge of said sheath when said trigger lies in the path of 25 travel of said pintle slide, said cover engaging said projection, during movement to closed position, to move said trigger out of the path of travel of said pintle slide.

7. In a loose leaf binder, a cover, a back member, a pintle slide movable longitudinally along one edge of said back member, a notch in said pintle slide, means pivoted to said back member, means automatically moving said first mentioned means into engagement with said notch 30 when said slide is moved to bring said notch into registration with said first mentioned means, means projecting from said first mentioned means beyond said pintle slide when said first mentioned means is engaged with said notch, said cover engaging said last mentioned means to automatically move said first mentioned means out of engagement with said notch when said cover is moved to closed position.

8. In a loose leaf binder, a back member, a cover hinged along one longitudinal edge of said back member, a pintle slide adjacent said longitudinal edge of said back member, the plane of said pintle slide being substantially perpendicular to the plane of said back member, said pintle 55 slide being provided with a recess, a spring urging said pintle slide inwardly, means for manually pulling said pintle slide outwardly against the

action of said spring, a trigger positioned out of the plane of said pintle slide, means automatically moving said trigger into the plane of said pintle slide and into said recess when said pintle slide has been moved outwardly a distance sufficient 5 to bring said recess into registration with said trigger, and means on said trigger projecting toward said cover, said cover engaging said last mentioned means, during movement to closed position, to move said trigger out of said recess 10 and out of the plane of said pintle slide.

9. In a loose leaf binder, a back plate, a pintle slide movable longitudinally of said back plate, a trigger comprising a flat bar pivoted to said back plate, a flange at the free end of said bar 15 bent at right angles thereto, and a pair of projections on said flange, one of said projections being adapted to engage said pintle slide to prevent longitudinal movement of said pintle slide, the other of said projections being engageable 20 by said cover when said cover is moved to closed position to move said first mentioned projection out of engagement with said pintle slide.

10. In a loose leaf binder, a back plate, a tubular sheath secured along one edge of said back 25 plate, a pintle slide in said sheath, said pintle slide being provided with a recess, and a trigger pivoted to said back plate, said trigger being movable substantially transversely in a plane parallel to said back plate into and out of said recess. 30

11. In a loose leaf binder, a back plate, a pintle slide movable longitudinally along one edge of said back plate, and a trigger pivoted to swing substantially transversely in a plane parallel to said back plate into and out of the path of travel 35 of said pintle slide, said trigger engaging said pintle slide to prevent movement of said pintle slide when said trigger is in the path of travel of said pintle slide.

12. In a loose leaf binder, a back plate, a tubular sheath secured along one edge of said back plate, a pintle slide in said sheath, a trigger pivoted to swing substantially transversely in a plane parallel to said back plate into the path of travel of said pintle slide, said trigger engaging said 40 pintle slide to prevent movement of said pintle slide, and spring means urging said trigger into the path of travel of said pintle slide. 45

13. In a loose leaf binder, a back plate, a pintle slide slidably secured along one edge of said back 50 plate, means tending to move said pintle slide to closed position, and a trigger movable substantially transversely in a plane parallel to said back plate, said trigger being adapted to engage said pintle slide to hold said slide in open position 55 against the action of said first mentioned means.

PAUL O. UNGER.
